UNITED STATES PATENT OFFICE.

BENJAMIN D. BURKE, OF AKRON, ALABAMA.

SALT AND PEPPER SHAKER TOP.

1,325,687.

Specification of Letters Patent. Patented Dec. 23, 1919.

Application filed April 30, 1918. Serial No. 231,691.

To all whom it may concern:

Be it known that I, BENJAMIN D. BURKE, a citizen of the United States, residing at Akron, in the county of Hale and State of Alabama, have invented certain new and useful Improvements in Salt and Pepper Shaker Tops; and I do hereby declare the following to be a full, clear, and exact description of the invention, such as will enable others skilled in the art to which it appertains to make and use the same.

My invention relates to improvements in closures especially adapted for use on dispensing receptacles, for holding finely divided solid material, such as granular or powdered solid material.

An important object of my invention is to provide a closure of the character described, which is normally retained closed, thus preventing loss from spilling, etc.

A further object of the invention is to provide a device of the above mentioned character, which is cheap to manufacture, neat in appearance, and of highly simplified construction.

Other objects and advantages of the invention, will be apparent during the course of the following description.

In the accompanying drawings forming a part of this specification and in which like numerals are employed to designate like parts throughout the same,

Figure 1 is a plan view of my improved closure,

Fig. 2 is a bottom plan view of the same,

Fig. 3 is a side elevation of the closure, in an open position,

Fig. 4 is a side elevation of the closure, in a closed position,

Fig. 5 is a central vertical sectional view through the device taken on line 5—5 of Fig. 1, and

Fig. 6 is an enlarged section taken on line 6—6 of Fig. 2.

In the drawings wherein for the purpose of illustration is shown the preferred embodiment of my invention, the numeral 10 designates a cover as a whole, which in use, is secured to the open end of a dispensing receptacle. It is obvious however, that in manufacture, the device may be made integral with the dispensing receptacle.

A plate 11 having a top plate 12 is provided with concentrically arranged perforations 13.

A coacting plate or cap 14 is arranged

upon the first named plate, and is secured thereto by a centrally arranged pivot 15. Adapted to register with the perforations of the plate 12, are concentrically arranged 60 perforations 16, in the cap 14.

Carried by the cap 14 is an annular flange 17, surrounding the plate 11. To restrict the rotary movement of the cap 14, the flange 17 thereof, is slotted as at 18 to receive a 65 projection 19 arranged upon the plate 11.

Secured to the outer side of the flange 17 is a finger piece 20.

A spring 21 anchored to the inner side of the plate 12, as at 22, serves to normally 70 retain the cap in a closed position. The plate 12 is provided with an arcuate slot 23 to receive a depending lug 24, carried by the cap 14 adjacent its outer edge, and adapted to contact with the free end of the 75 spring. The free end portion of the spring is hooked to prevent the same from accidental displacement. Particular attention is called to the fact that the flexing of the spring in no way obstructs any of the perforations of the cover.

While I have shown and described the preferred embodiment of my invention, it is understood that I may make such minor changes in arrangement and construction of 85 parts as will remain within the spirit of the invention and the appended claim.

Having thus described my invention, what I claim is:

A closure for dispensing receptacles including a plate having a depending annular flange, a cap pivotally mounted on the plate and having an annular flange surrounding said first named annular flange, said plate being provided with an arcuate slot, a depending lug carried by said cap adjacent its outer edge and extending through said arcuate slot, a wire spring anchored at one end to the under side of said plate and partly traversing the same and having its free end portion hooked and engaging said depending lug, said plate and cap being provided with openings adapted for registration, means to limit the rotary movement of the cap, and a finger piece carried by said second named annular flange.

In testimony whereof I affix my signature in presence of two witnesses.

BENJAMIN D. BURKE.
